UNITED STATES PATENT OFFICE.

WILLIAM P. STALLCUP, OF COMANCHE, TEXAS.

EVAPORATOR AND FURNACE.

SPECIFICATION forming part of Letters Patent No. 367,120, dated July 26, 1887.

Application filed April 16, 1886. Serial No. 199,121. (No model.)

To all whom it may concern:

Be it known that I, WILLIAM P. STALLCUP, a citizen of the United States, residing at Comanche, in the county of Comanche and State of Texas, have invented new and useful Improvements in Evaporators and Furnaces, of which the following is a specification, reference being had to the accompanying drawings.

My invention relates to an improvement in evaporating-pans and furnaces for boiling molasses; and it consists in the peculiar construction and combination of devices that will be more fully set forth hereinafter, and particularly pointed out in the claims.

15 In the drawings, Figure 1 is a top plan view. Fig. 2 is a vertical longitudinal sectional view taken through the evaporating-pan and the furnace. Fig. 3 is a transverse sectional view of the evaporating-pan. Fig. 4 is a detail view 20 showing the manner of connecting the parts of the furnace together.

A represents the furnace, which has sides B, made of cast or wrought metal, and provided at their ends with recesses C. On the 25 inner sides of the sides are made grooves D and E. The grooves D are inclined upwardly and are located at a suitable distance from the inclined lower rear edges of the sides, and the grooves E are horizontal and are located at a 30 suitable distance above the lower edges of the front ends of the sides.

F represents a bottom plate, which is located between the sides B, and the edges of which enter the grooves D of the sides.

35 G represents the front side or wall of the furnace, which is made of cast or wrought metal, and is provided at its ends with projections or shoulders g, that enter the recesses C of the sides. This front wall is provided also 40 with a lower opening, H, forming the door to the ash-pit, and a door, I, above the opening H, forming a door of the fire-box. The rear wall, K, of the furnace is also formed of wrought or cast metal, and is provided with 45 projections that enter the recesses at the rear ends of the side walls, and has a vertically-projecting collar, L, for the attachment of the smoke-pipe. The side and end plates or walls 50 of the furnace are secured together by vertical bolts M, which pass through aligned openings made in the ends of the plates, as shown,

thereby firmly securing the sides and ends of the furnace together, and permitting them to be readily taken apart, by first withdrawing the bolts. The grate-bars N have their ends secured in the grooves E. The openings H and I are provided with suitable hinged doors. By opening or closing the door H the draft may be regulated, and the door I permits fuel to be fed to the fire.

N' represents the evaporating-pan. The sides O of the pan are made of wood and are provided on their opposing sides with vertical grooves P. The bottom and ends of the pan are formed of sheet metal, the ends of which 65 are bent at right angles and secured in the end grooves P, while the edges of the bottom of the pan are bent upwardly at right angles and bear against the lower outer edges of the sides O and are securely tacked thereto. Brace- 70 strips S are placed under the bottom at the sides thereof. The said brace-strips are triangular or convex in cross-section to form the inclined beveled sides s and the flat bottom sides s'. Vertical bolts T pass through the 75 sides O, through the edges of the bottom plate, and through the strips S, and serve to clamp the bottom plate firmly to the lower edges of the sides O, so as to prevent the pan from leaking. The pan is divided into three compartments by means of transverse vertical partition-walls U, which are made of sheet metal 80 and are inserted in the intermediate grooves, P, and the said partition-walls are provided at one side with vertically-movable gates V. 85 Transverse bolts W pass through the side walls and connect the same together, thereby firmly bracing the pan against lateral strain. The transverse bolts at the ends of the pan are on the outer sides of the end walls thereof, and 90 thus serve to brace the latter. The compartment X at one end of the evaporating-pan immediately over the fire-box is left clear, and forms the skimming-chamber, in which the impurities and froth, which arise from the surface 95 of the molasses while being boiled, are skimmed off. The other compartments, Y and Z, are each divided by means of vertical plates Z' into tortuous channels, the said plates extending nearly but not quite across the evaporating-pan, leaving openings alternately at opposite sides thereof.

The operation of my invention will be readily understood by persons skilled in the art from the foregoing description and by reference to the accompanying drawings.

Having thus described my invention, I claim—

The furnace for evaporators, comprising the side walls B, provided on their opposing faces at one end with the horizontal grooves E, and the inclined rearwardly-extending grooves D, communicating at their lower ends with the grooves E, the front end wall, G, having the doors H and I, the rear end wall, K, having the vertically-projecting collar L for the at-

tachment of a smoke-pipe, the bottom plate 15 having its edges secured in the inclined grooves D, and the grate-bars having their ends secured in the grooves E, the side and end walls being bolted together and thereby rendered separable, substantially as described. 20

In testimony that I claim the foregoing as my own I have hereto affixed my signature in presence of two witnesses.

WILLIAM P. STALLCUP.
